INSOLE FOR SHOES

George E. Musebeck, Danville, Ill., assignor to
 Musebeck Shoe Company, Danville, Ill., a corporation

Application December 28, 1939, Serial No. 311,327

2 Claims. (Cl. 36—71)

This invention relates to an insole for orthopedic shoes.

In my prior Patent No. 1,916,198, issued July 4, 1933, I have disclosed an insole adapted to correct certain foot faults and a method of manufacturing said insole. This invention pertains to the same general type of insole for correcting the same foot troubles. More particularly this invention relates to the stitch receiving means in an insole having two pieces of material one of which has the outline of a normal insole with arch supporting extension and the other of which is assembled beneath said first piece to provide additional thickness where needed for certain orthopedic results.

One object of the present invention is to simplify and improve the stitch receiving means and methods of manufacturing the same in insoles of this type.

Other objects and the full nature thereof will be understood from the accompanying drawing and the following description and claims:

Fig. 1 is a bottom view of an insole constructed in accordance with the invention. Figs. 2, 3 and 4 are sectional views taken on the lines 2—2, 3—3, and 4—4, respectively, of Fig. 1.

In the preferred form of the invention shown in the drawing there is provided a piece 10 of relatively thick leather having the outline of a normal insole with arch supporting extension 11 opposite the inner shank portion and part of the heel. A welt receiving recess 12 and an outwardly directed stitching channel 13 are cut in the under surface of said piece along the outer edge of the shank portion and about the forepart of the piece. Said recess and channel terminate at the point 14 adjacent the point from which the arch support 11 breaks. Together they form the usual stitch receiving rib 15.

Beneath the piece 10 there is assembled a wedge piece 16 extending beneath the inner edge of the foot from the ball portion to the heel and adapted to provide corrective pressures for the foot ills described in my prior patent before mentioned. The two pieces 10 and 16 are preferably securely cemented together. The wedge piece 16 is reduced in thickness along its outer edge to provide a lip 17 which may be turned downwardly to serve as a stitch receiving rib. A cut 18 at the breast of the heel terminates the lip 17. At the point 14 the material of the piece 16 is forced into the channel 13 as best seen in Fig. 2 so that the lip 17 lies against the rib 15 and forms therewith a substantially continuous stitch receiving means.

In some cases it is desirable to reinforce the

lip 17 and this may be accomplished most advantageously by turning down a rib 19 (Fig. 3) by means of an inwardly directed cut 20 in the under surface of the piece 10 and extending parallel with the edge of the piece 16. The rib 19 is cemented to the lip 17 to provide a strong and durable stitching rib secured to both pieces 10 and 16.

In the manufacture of the insole just described, 10 the welt receiving recess 12 and channel 13 may be cut by well known machinery as in my prior patent before mentioned. The machine operation necessary to channel the wedge piece corresponding to piece 16 is eliminated and a saving of 15 labor is obtained. When the reinforcing rib 19 is used it may be most easily formed after the pieces 10 and 16 are secured together at which time the edge of the piece 16 may form a guide in making the cut. The cut 20 need not be as deep as the standard channelling cut 13 since the rib 19 serves only to reinforce the lip 17. This cut does not therefore materially weaken the arch support extension and may readily be made by hand if suitable machinery is not available.

The invention claimed is:

1. An insole for shoes comprising a piece of sole material having the outline of a normal insole with arch supporting extension, and a wedge piece assembled therewith as a unitary structure, said wedge piece being beneath the first and extending beneath one side of the shank portion of the foot, and having its edge adjacent said arch support extension turned downwardly to form a stitch receiving rib, and said first piece having an outwardly directed cut along the outer edge of the shank and about the forepart of the foot forming a stitch receiving rib substantially continuous with said first mentioned rib, and having an inwardly directed cut forming a rib parallel with said first mentioned rib and secured thereto.

2. An insole for shoes comprising a piece of sole material having the outline of a normal insole with arch supporting extension, and a wedge piece assembled therewith as a unitary structure, said wedge piece being beneath the first and extending beneath one side of the shank portion of the foot, and having its edge adjacent said arch support extension turned downwardly to form a stitch receiving rib, and said first piece having an inwardly directed cut forming a rib parallel with said first mentioned rib and secured thereto.
